SEPARABLE END FASTENER

Ernest Clark, Beeston, England, assignor to
 United-Carr Fastener Corporation, Cambridge,
 Mass., a corporation of Massachusetts

Application January 19, 1935, Serial No. 2,525

11 Claims. (CL 24—205)

The present invention relates to improvements in separable fastener installations and particularly to improvements in such installations having separable end fastening means which permit complete separation of the stringers of the installation at desired times.

More particularly the invention relates to improvements in the construction of the end fastening means and to the manner of connecting them to the stringers, and to the improved relationship of the end fastening means to the slider and fastening elements, to the end that the construction of such separable fasteners as a whole is improved generally and is rendered more satisfactory in operation.

More specific objects and advantages of the invention will be apparent to those skilled in that art having reference to the accompanying drawing illustrating certain preferred embodiments of the invention.

In the drawing

Figure 1 is an enlarged elevation of a portion of a multiple operated fastener installation illustrating one embodiment of the invention.

Fig. 2 is a similar view of one of the stringers and the female member of the end fastening device.

Fig. 3 is a view similar to Fig. 1 illustrating the parts ready to be moved into interlocking engagement.

Fig. 4 is a horizontal sectional view taken on the line 4—4 of Fig. 1.

Fig. 5 is a similar view taken on the line 5—5 of Fig. 3 but with the end fastener elements shown in closed or interlocked position.

Fig. 6 is an enlarged elevation of the male end fastener element.

Fig. 7 is an edge view thereof.

Fig. 8 is an enlarged elevation of the female end fastener element.

Fig. 9 is an edge view thereof looking in the direction of the open edge.

Fig. 10 is an upper edge view thereof.

Fig. 11 is a lower edge view thereof.

Fig. 12 is an elevation of the male end fastener element according to a modified form of the invention.

Fig. 13 is an edge view thereof, and

Fig. 14 is an upper edge view thereof.

The invention is particularly adapted to and is best illustrated as applied to separable fasteners of the type employing a pair of separable stringers 10 which may be completely separated at specified times, which stringers are provided with fastening elements 11, of any desired form

and construction adapted to be progressively interlocked or released upon movement of a cooperating slider 12. In the illustrated form of the invention the stringers 10 may be of fabric, or other flexible material, and the fastening elements 11 may be suitably connected to the edges of the stringer, in such manner that the fastening elements on one of the stringers may be positioned between and interlocked with the fastening elements on the opposite stringer. The slider 12 may be of any suitable construction, employing the usual spaced front and back plates 13 between which the fastener elements 11 move.

According to the invention, near one end of the stringers 10, preferably the lower end, there is provided a pair of separable end fasteners comprising a male member 14 and female member 15, each of said members 14, 15 being advantageously formed of thin sheet metal, and to embrace and be secured to the edge of the stringers by suitable means, as for example rivets 16. Preferably there are two or more of these fastening means 16 for each of the members 14, 15 and stop members 17 may be secured to the edge portions of one or more of the stringers 10 and adapted for engagement with one or more of the members 14, 15 to hold the members in proper position with reference to the fastening elements 11.

The male end fastening member 14 may advantageously be formed of a single piece of thin sheet metal, bent to U-shaped form to embrace the edge portion of the stringer 10 to which it is to be secured. A pair of hooks 18 are formed on the male member, presenting spaced interlocking hooks on opposite sides of the male end fastening element 14. Advantageously these hooks 18 may be formed by slitting a portion of the blank forming the male end fastening member, as at 19, and utilizing the portion of the metal so slit to form the interlocking hooks 18.

The cooperating female end fastening member 15 may be formed of sheet metal and as illustrated is made of two pieces secured to the opposite sides of the stringer 10 so as to present spaced sides or flanges 20 projecting laterally beyond the edge of the stringer 10. These flanges receive between them the male end fastening member 14. Preferably an edge portion of the sides or flanges 20 may be flared outwardly as at 21 to act as a guide and facilitate the entering of the male member 14 between the flanges 20 of the female member 15. The female end fastener is preferably provided with means adapted for interlock-

ing engagement with the male member, to prevent accidental separation of the members when in locked position, and preferably such means may comprise laterally projecting locking ears 5 22 on each of the plates 20, extending laterally beyond the body of the female end fastener 15 and adapted to be positioned between the hooks 18 and the body of the male fastener 14. The ears 22 may advantageously be formed with angular extensions 23 adapted to be positioned behind the hooks 18 and lock the two fasteners against a straight lateral pull.

The laterally extending ears 22 and the angularly disposed extension 23 on each of the plates 15 20 provide an entering throat 24 on each of the plates 20, between the ears 22 and the guides 21 permitting entry of the hook members 18 of the male end fastener 14 into interlocking engagement with the ears. As will be apparent from 20 Fig. 3 the end fasteners are connected, first by bringing the two together in an angular position as shown, so that the lower end of the male end fastener will enter between the curved portions or guides 21 of the female end fastener. Thereupon, a relative rotative movement of the male end fastener 14 with respect to the female end fastener 15 will cause the hook portions 18 to enter the throat 24 and be positioned below the ears 22 and behind the extension 23, securely locking the members 14 and 15 in position. As will be apparent from Figs. 1, 3 and 8, a portion 25 of the female member 15 extends outwardly beyond the inner edge of the throat 24 and prevents accidental unlocking of the end fastener by a 35 relative longitudinal shifting movement.

A slightly modified form of male end fastener 14 is illustrated in Figs. 12 to 14 inclusive wherein the end fastener is formed from a single blank of metal bent into U-shaped form providing plates 40 26 on opposite sides of the stringer 10 and which are connected by the portion 27. In this instance I have cut out the material at 28 to form hooks 29 extending from the lower edges of the cut-out 28 instead of at the upper edges as in the fastener 14. 45 This arrangement is slightly easier to manufacture than the other shown in Figs. 6 and 7.

In applying the end fasteners 14, 15 to the stringers, they are arranged so that one end of each is in contact with the endmost fastening element 11 on each stringer 10 (Figs. 1, 2 and 3), and thus the end fasteners act to hold the endmost fastening elements 11 in proper positions. Thus a stop member 17 securely fixed to a stringer 50 10 engaging the opposite end of an end fastener acts, in conjunction with the fastening devices 16 and a fastener element 11, to provide against loosening or shifting of the end fastener member 15. Thus it is not as essential to provide a member 17 with the end fastener member 14 because 55 it has a better grip on its stringer 10, as shown in Figs. 5, 6 and 7.

Furthermore, as will be apparent from the illustration of Figs. 3 and 5, the inner edge of the male end fastener 14 is entered between the 60 spaced plates 13 of the slider 12 as it is moved into locking engagement with the female end fastener 15. Thus as the end fasteners are locked together, the endmost fastening elements 11 of each stringer are accurately positioned with respect to each other and to the slider 12 which is held in proper alignment and positioned by engagement with the male end fastener 14. As a result I have provided an improved end separable fastening means which is strong, durable and so 65 constructed that the operation thereof is appar-

ent and accurately aligns the fasteners 11 prior to the slider being moved to engage the fasteners 11.

As has been described above, the end fastener elements 14, 15 may be made in one-piece or two-piece units from sheet metal and are simple and durable in construction, inexpensive to manufacture and are readily attached to the stringers.

While one preferred form of the invention has been illustrated and described, the invention is not to be limited thereby, because the scope thereof is best defined by the following claims:

1. A separable fastening device having two stringers each having a series of fastening elements attached to an edge, a slider for engaging and disengaging the fastening elements, end fastener means detachably coupling said stringers, said end fastener means including a male and a female member adapted for interlocking engagement with each other, said female member including a pair of plates on opposite sides of one stringer, at least one of said plates having an integral ear extending laterally from said plate and a projection disposed beneath said ear and spaced therefrom whereby a throat is presented by said ear and said projection, and said male member provided with a hook portion adapted to be positioned within the throat defined by the ear and projection of said female member and embrace a portion of said ear.

2. A separable fastening device having two stringers each having a series of fastening elements attached to an edge, a slider for engaging and disengaging the fastening elements, end fastener means detachably coupling said stringers, said end fastener means including a male and a female member adapted for interlocking engagement with each other, said female member having an integral L-shaped ear extending laterally therefrom and a projection positioned beneath said ear and spaced from the same whereby a throat is presented by said ear and said projection, and said male member presenting an integral hook portion adapted to be positioned within the throat defined by said L-shaped locking device.

3. A separable fastening device having two stringers each having a series of fastening elements attached to an edge, a slider for engaging and disengaging the fastening elements, end fastener means detachably coupling said stringers, said end fastener means including a male and a female member adapted for interlocking engagement with each other, said female member including a pair of plates on opposite sides of one stringer, at least one of said plates having an integral L-shaped ear extending laterally from one edge thereof and a projection extending laterally from the same edge as said ear and spaced from said ear whereby a throat is presented by said ear and said projection, and said male member including a pair of plates on opposite sides of the other stringer, at least one of said plates presenting an integral hook portion adapted to be positioned within the throat defined by said L-shaped locking device.

4. A separable fastening device having two stringers each having a series of fastening elements attached to an edge, a slider for engaging and disengaging the fastening elements, end fastener means detachably coupling said stringers, said end fastener means including a male and a female member adapted for interlocking engagement with each other, said fe-

5 male member including a pair of plates on opposite sides of one stringer, at least one of said plates having an integral L-shaped ear extending laterally therefrom, said plate having a flared portion located below said ear whereby a throat is presented by said ear and said flared portion, and said male member including a pair of plates on opposite sides of the other stringer, at least one of said plates presenting a hook portion bent 10 from the plane of said plate and adapted to be positioned within the throat defined by said L-shaped locking device.

10 5. A separable fastening device having two stringers each having a series of fastening elements attached to an edge, a slider for engaging and disengaging the fastening elements, end fastener means detachably coupling said stringers, said end fastener means including a male and a female member adapted for interlocking engagement with each other, said female member including a pair of plates on opposite sides of one stringer, each of said plates having an integral L-shaped ear extending laterally therefrom and each of said plates having a 20 flared portion located below said ear whereby a throat is presented by said ears and said flared portions, and said male member made of one piece of sheet metal including a pair of plates on opposite sides of the other stringer, each of 25 said plates presenting an integral hook portion adapted to be positioned within the throat presented by said ears and said flared portions and the plates of said male member presenting a metal surface for engagement with the plates of 30 said female member.

35 6. A separable fastening device having two stringers each having a series of fastening elements attached to an edge, a slider for engaging and disengaging the fastening elements, end fastener means detachably coupling said stringers, said fastener means including a male and a female member adapted for interlocking engagement with each other, said female member including a pair of plates on opposite sides 40 of one stringer, each of said plates having an integral L-shaped ear extending laterally from one edge thereof and a projection extending laterally from the same edge as said ear and spaced from said ear whereby throats are 45 formed by the ears and projections of said respective plates for receiving cooperating locking means of said male member.

50 7. A separable fastening device having two stringers each having a series of fastening elements attached to an edge, a slider for engaging and disengaging the fastening elements, end fastener means detachably coupling said stringers, said end fastener means comprising male and female members, said male member made of one 55 piece of sheet metal having a pair of integral hook portions disposed on opposite sides thereof for fastening engagement with cooperating means located on said female member, each of said hook portions having a free end portion

disposed in spaced substantially parallel relation to said respective side.

8. A separable fastening device having two stringers each having a series of fastening elements attached to an edge, a slider for engaging and disengaging the fastening elements, end fastener means detachably coupling said stringers, said end fastener means comprising male and female members, said male member made of one piece of sheet metal having a pair of plates on opposite sides of one of said stringers and a hook-shaped portion integral with each of said plates and disposed on opposite sides of said stringer, each of said hook-shaped portions having a free end portion disposed in spaced substantially parallel relation to said respective plate.

9. A separable fastening device having two stringers each having a series of fastening elements, a slider for engaging and disengaging the fastening elements, end fastener means detachably coupling said stringers, said end fastener means comprising male and female members, said male member made of one piece of sheet metal having a pair of plates on opposite sides of one of said stringers, and a hook-shaped portion integral with each of said plates and disposed on opposite sides of said stringer, each of said hook-shaped portions joining the material of said respective plate intermediate top and bottom edges of said plate.

10. A separable fastening device having two stringers each having a series of fastening elements attached to an edge, a slider for engaging and disengaging the fastening elements, end fastener means detachably coupling said stringers, said end fastener means including a male and female member adapted for interlocking engagement with each other, said male member having a pair of spaced apart plates disposed on opposite sides of one stringer, at least one of said plates having an integral hook portion formed of material intermediate top and bottom edges of said plate and offset laterally relative to the broad face of said plate, said hook portion being operative upon relative rotative movement of said end fastener members for interlocking said male member with said female member.

11. A separable fastening device having two stringers each having a series of fastening elements attached to an edge, a slider for engaging and disengaging the fastening elements, end fastener means detachably coupling said stringers, said end fastener means including a male and female member adapted for interlocking engagement with each other, said male member having a pair of spaced apart plates on opposite sides of one stringer, at least one of said plates having a hook portion formed of material intermediate top and bottom edges thereof, said hook portion being bent from the plane of said plate for fastening engagement with cooperating means located on said female member.

ERNEST CLARK.
